UNITED STATES PATENT OFFICE.

WILLIAM NOBLE, OF NORTHAMPTON, MASSACHUSETTS, ASSIGNOR TO PRO-PHY-LATIC BRUSH COMPANY, OF NORTHAMPTON, MASSACHUSETTS, A CORPORATION OF MASSACHUSETTS.

POSITIONING MECHANISM FOR BRUSH MACHINES.

Application filed February 24, 1925. Serial No. 11,134.

The present invention has for its object an improvement on the positioning mechanism forming part of the brush machine shown in patent to Herman M. Schwartz No. 1,125,187, dated January 19, 1915. In that machine there is shown a positioning mechanism comprising essentially a travelling chain which carries the brush holders, horizontal and vertical slides for moving the chain in two directions at right angles to each other, a cam shaft and cams on the shaft to give the two slides their proper motions. The so-called vertical slide which is the one which moves the travelling chain up and down is moved by a pivoted lever actuated by the vertical cam. This lever has on its front end a roller which engages one side of a slot in the upper end of the vertical slide, so that the vertical slide in effect hangs from the said roller. The movement of the horizontal cam moves the vertical slide horizontally, this movement being permitted by the said slot and roller. It has been found in practice that this arrangement is not altogether satisfactory as the movement of the cam lever on which the vertical slide is hung changes the angle of contact of the roller with the side of the slot and results in cramping and uneven and rapid wear which affects the accuracy of the machine. Furthermore, the accuracy of the machine is affected by the angle of the lever relative to the vertical plate. The present invention therefore has for its object to provide mechanism for actuating the vertical slide of the positioning mechanism of a brush machine which will at the same time permit the proper horizontal movements without cramping and without diminishing the accuracy of the machine.

In the following description and in the accompanying drawings I have shown the invention as embodied in a brush machine of the type shown in the said patent to Schwartz as that is the manner in which the invention has been put into actual practice but it will be understood that the invention is not limited to this construction since it is capable of other embodiments.

60 In the drawings:

Fig. 1 is a side elevation of the portions of the positioning mechanism of a brush machine of the type shown in the said Schwartz patent, said positioning mecha-

nism being provided with the improvements 65 embodied in the present invention.

Fig. 2 is a front elevation of the parts shown in Fig. 1.

Fig. 3 is a section on line 3—3, Fig. 2.

Fig. 4 is a section on line 4—4, Fig. 2. 60
Referring to the drawings:

At A is shown the travelling carrier, at B the vertical slide, at C the horizontal slide, at D the vertical cam, at E the horizontal cam and at F the cam shaft of a 65 brush machine of the said Schwartz type. The vertical cam acts upon a cam roller 11 held in a fork 12 forming part of a lever 13. The rear end of the lever 13 is pivoted at 14 to a fixed part of the machine and 70 has on its front end a roller 15. This roller contacts with the under side of a swinging block 16 which is furnished with trunnions 17, 17 inserted in holes in two L-shaped blocks 18. These L-shaped blocks 18 are secured by screws 19 to the upper part of the vertical slide B adjacent the cut-away portion 20 thereof. The swinging block 16, 75 when in place, forms in effect the upper side of the slot which affords sufficient space for movement of the roller 15 back and forth relative to the slide, this movement being produced by the action of the horizontal cam E.

In the operation of the machine the vertical cam acting through the roller 11 swings the cam lever 13 about its pivot 14 and thus raises and lowers the slide B. At the same time the horizontal cam E moves the vertical slide B sidewise, this movement being permitted by the slot 20. As the vertical cam D revolves and the lever 13 swings about its pivot 14 its angle to the vertical slide B as viewed in side elevation, see Figs. 1 and 3, 85 changes and the swinging block 16 swings on 90 its trunnions and accommodates itself to this change in angle maintaining a line contact with the roller in all positions. It will, therefore, be seen that the position vertically 95 of the slide is not affected by the angle of the roller since the swinging action of the block 16 permits the block to adjust itself to all positions of the lever. It will also be seen that the roller 15 contacts throughout 100 its entire length with the under surface of the block 16 and therefore the wear is distributed throughout the entire length of the roller and is not concentrated in any one 105

spot nor is there more wear on the edges than on the middle. The result of this construction is that the machine is much more accurate in its operation and continued use of the machine does not affect the vertical spacing of the rows of holes in the brush which is produced by the machine.

What I claim is:

1. In a positioning mechanism for a brush machine and in combination with a cam thereof, a slide, a lever actuated by the cam to move the slide, said slide being movable transversely of the lever and a swinging block secured to the slide to provide a contact member for the lever adjustable to variations in angle between the cam actuated lever and the slide.

2. In a positioning mechanism for a brush machine and in combination with the horizontal and vertical slides thereof and the respective horizontal and vertical cams

therefor, a lever actuated by one of said cams to move the corresponding slide and a swinging block secured to the said slide and providing a uniform area of contact between the lever and the said slide while permitting movement of said slide in a direction at right angles thereto by the other cam.

3. In a positioning mechanism for a brush machine and in combination with the horizontal and vertical slides thereof and the respective horizontal and vertical cams therefor, a lever actuated by the vertical cam to lift and lower the vertical slide and having a roller thereon, a swinging block secured to said slide and providing a uniform area of contact between said roller and said slide while permitting movement of said vertical slide horizontally by the horizontal cam.

In testimony whereof I affix my signature.

WILLIAM NOBLE.
